(57) **CLAIM**

We claim the ornamental design for a rack mounted electronic device, as shown and described.

DESCRIPTION

FIG. 1 is a perspective view of a rack mounted electronic device according to a first embodiment;

FIG. 2 is a front elevational view of the rack mounted electronic device according to the first embodiment;

FIG. 3 is a rear elevational view of the rack mounted electronic device according to the first embodiment;

FIG. 4 is a top plan view of the rack mounted electronic device according to the first embodiment;

FIG. 5 is a bottom plan view of the rack mounted electronic device according to the first embodiment;

FIG. 6 is a left side elevational view of the rack mounted electronic device according to the first embodiment;

FIG. 7 is a right side elevational view of the rack mounted electronic device according to the first embodiment;

FIG. 8 is an enlarged partial view of the rack mounted electronic device according to the first embodiment, the view being taken from FIG. 1;

FIG. 9 is an enlarged partial view of the rack mounted electronic device according to the first embodiment, the view being taken from FIG. 2;

FIG. 10 is an enlarged partial view of the rack mounted electronic device according to the first embodiment, the view being taken from FIG. 4;

FIG. 11 is an enlarged partial view of the rack mounted electronic device according to the first embodiment, the view being taken from FIG. 5;

FIG. 12 is a perspective view of a rack mounted electronic device according to a second embodiment;

FIG. 13 is a front elevational view of the rack mounted electronic device according to the second embodiment;

FIG. 14 is a rear elevational view of the rack mounted electronic device according to the second embodiment;

(Continued)

FIG. 15 is a top plan view of the rack mounted electronic device according to the second embodiment;
 FIG. 16 is a bottom plan view of the rack mounted electronic device according to the second embodiment;
 FIG. 17 is a left side elevational view of the rack mounted electronic device according to the second embodiment;
 FIG. 18 is a right side elevational view of the rack mounted electronic device according to the second embodiment;
 FIG. 19 is an enlarged partial view of the rack mounted electronic device according to the second embodiment, the view being taken from FIG. 12;
 FIG. 20 is an enlarged partial view of the rack mounted electronic device according to the second embodiment, the view being taken from FIG. 13;
 FIG. 21 is an enlarged partial view of the rack mounted electronic device according to the second embodiment, the view being taken from FIG. 15;
 FIG. 22 is an enlarged partial view of the rack mounted electronic device according to the second embodiment, the view being taken from FIG. 16;
 FIG. 23 is a perspective view of a rack mounted electronic device according to a third embodiment;
 FIG. 24 is a front elevational view of the rack mounted electronic device according to the third embodiment;
 FIG. 25 is a rear elevational view of the rack mounted electronic device according to the third embodiment;
 FIG. 26 is a top plan view of the rack mounted electronic device according to the third embodiment;
 FIG. 27 is a bottom plan view of the rack mounted electronic device according to the third embodiment;
 FIG. 28 is a left side elevational view of the rack mounted electronic device according to the third embodiment;
 FIG. 29 is a right side elevational view of the rack mounted electronic device according to the third embodiment;
 FIG. 30 is an enlarged partial view of the rack mounted electronic device according to the third embodiment, the view being taken from FIG. 23;
 FIG. 31 is an enlarged partial view of the rack mounted electronic device according to the third embodiment, the view being taken from FIG. 24;
 FIG. 32 is an enlarged partial view of the rack mounted electronic device according to the third embodiment, the view being taken from FIG. 26;
 FIG. 33 is an enlarged partial view of the rack mounted electronic device according to the third embodiment, the view being taken from FIG. 27;
 FIG. 34 is a perspective view of a rack mounted electronic device according to a fourth embodiment;
 FIG. 35 is a front elevational view of the rack mounted electronic device according to the fourth embodiment;
 FIG. 36 is a rear elevational view of the rack mounted electronic device according to the fourth embodiment;
 FIG. 37 is a top plan view of the rack mounted electronic device according to the fourth embodiment;
 FIG. 38 is a bottom plan view of the rack mounted electronic device according to the fourth embodiment;
 FIG. 39 is a left side elevational view of the rack mounted electronic device according to the fourth embodiment;
 FIG. 40 is a right side elevational view of the rack mounted electronic device according to the fourth embodiment;
 FIG. 41 is an enlarged partial view of the rack mounted electronic device according to the fourth embodiment, the view being taken from FIG. 34;

FIG. 42 is an enlarged partial view of the rack mounted electronic device according to the fourth embodiment, the view being taken from FIG. 35;

FIG. 43 is an enlarged partial view of the rack mounted electronic device according to the fourth embodiment, the view being taken from FIG. 37; and,

FIG. 44 is an enlarged partial view of the rack mounted electronic device according to the fourth embodiment, the view being taken from FIG. 38.

The broken lines showing portions of the rack mounted electronic device are included to illustrate portions of the article and form no part of the claimed design.
